United States Patent Office.

WILLIAM A. DEVON, OF RICHMOND, NEW YORK.

Letters Patent No. 67,419, dated August 6, 1867; antedated July 23, 1867.

IMPROVED APPARATUS FOR RAISING AND LOWERING SHIPS' BOATS.

The Schedule referred to in these Letters Patent and making part of the same.

TO ALL WHOM IT MAY CONCERN:

Be it known that I, WILLIAM A. DEVON, of Port Richmond, in the county of Richmond, and State of New York, have invented a certain new and useful Improvement in Apparatus for Raising or Lowering and Suspending Ships' Boats, of which the following is a full, clear, and exact description, reference being had to the accompanying drawing, forming part of this specification, and in which—

Figure 1 represents an interior side elevation of my improved apparatus in its connection with a ship's boat, and as attached to the bulwarks of a vessel, and

Figure 2, a partly sectional view at right angles to fig. 1, showing in black and red lines the boat and davit to which it is attached in inner and outer positions.

Like letters indicate like parts in both figures.

My improvement has reference to a method of raising or lowering and suspending ships' boats, such as described in Letters Patent of the United States, No. 57,877, issued to me and, bearing date the 11th day of September, 1866, in which the ropes of the end tackles are rove through a block connected with an intermediate or central davit, and the loose ends or portions of said ropes are attached to or made to bite on a rotating barrel to facilitate raising or lowering of the boat, and by which method increased facility and security are obtained by conjointly working both end tackles from a common centre, thereby avoiding tipping of either end of the boat, besides securing other advantages, as fully set forth in said patent. The nature of my invention in this connection consists in wholly dispensing with end davits for support of the end tackle-blocks and swinging connection of the boat at its opposite ends to the bulwarks of the vessel, and employing in place thereof an intermediate or central davit with a cross-rod or beam carrying the end blocks, and whereby the boat may not only be raised or lowered from a common centre, but by the working of the one davit may be swung in or out of the ship with security and dispatch.

Referring to the accompanying drawing A represents the side or bulwarks of a ship, and B its boat, held in suspension by or to an intermediate or central swinging davit, C, having connected with it a block, D, and cross-rod or beam E, carrying at or near its ends blocks G G, through which and corresponding lower running blocks H H, that hook on the boat at its ends, the ropes b b' of the end tackles are rove, and after being passed over and through the intermediate block D, are brought downwards through suitable pulleys, blocks, or guides e to a winch or barrel, I, to which said ropes are attached, or on which they have given them bite to secure their joint operation in an advantageous and controllable manner, as fully set forth in the Letters Patent before referred to; or the end tackle ropes thus passed through the block D, and uniting at a common centre, may be otherwise worked to secure a uniform raising or lowering of both ends of the boat for the more effectual prevention of accident than is attainable by a separate application and working of the end ropes, as, for instance, instead of the barrel I the two ropes may be given a hitch round any suitable fixture. J J are brace rods, uniting the cross-bar or beam E with the davit C, at or near its base or bearing, and so as to swing in common with said davit, the same serving to strengthen or stiffen the apparatus.

By this my improvement not only is uniformity secured in raising or lowering both ends of the boat from a common centre in a manageable manner, with safety and dispatch, but, instead of having to swing out or in, first one end davit and then the other, to bring the boat to the required position, which, as boats are ordinarily suspended, is a matter of no little difficulty or labor, especially in a rough sea, when the ship is rolling, the boat may be swung out or in, as represented by black and red lines in fig. 2, by the swinging of a single davit, C, which may be effected by a hand-spike or bar, d, by guys or any other suitable means.

What is here claimed as new and useful, and sought to be secured by Letters Patent, is—

The combination of the davit C with its cross-bar or beam E, and blocks D G G, arranged for operation together, in connection with the ropes of the two end tackles, and swinging from a common centre, substantially as and for the purpose or purposes herein set forth.

WM. A. DEVON.
